Primary Examiner — Michael A Maharajh

(57) **CLAIM**

The ornamental design for a massage head of massage apparatus, as shown and described.

DESCRIPTION

Figure 1.1 is a front, right, and top perspective view of a massage head of massage apparatus showing our new design;

Figure 1.2 is a back, left, and bottom perspective view thereof;

Figure 1.3 is a front view thereof;

Figure 1.4 is a back view thereof;

Figure 1.5 is a left view thereof;

Figure 1.6 is a right view thereof;

Figure 1.7 is a top view thereof;

Figure 1.8 is a bottom view thereof; and

Figure 1.9 is a perspective view of a massage head of massage apparatus shown in a condition of use thereof.

The broken lines of the massage apparatus shown in Figure 1.9 are for the purpose of illustrating environmental structure, which form no part of the claimed design.

1 Claim, 9 Drawing Sheets
